UNITED STATES PATENT OFFICE.

JOSEPH M. KRYL, OF CHICAGO, ILLINOIS.

FIRE-ESCAPE.

1,346,787.

Specification of Letters Patent. Patented July 13, 1920.

Application filed September 4, 1917. Serial No. 189,527.

To all whom it may concern:

Be it known that I, JOSEPH M. KRYL, a citizen of the United States, residing at Chicago, in the county of Cook and State of Illinois, have invented a certain new and useful Improvement in Fire Escapes, of which the following is a full, clear, concise, and exact description, reference being had to the accompanying drawings, forming a part of this specification.

The invention relates to improvements in fire escapes and has for its object the provision of a compact arrangement of the stairs or ladder, and the means for raising it.

It is an object of the invention to arrange the means which raises and holds the ladder in an elevated position, so that this portion will not be compelled to occupy a position and extend in a direction opposite to that in which the ladder extends. The above named arrangement in some instances necessitates the portion which holds the ladder in elevated position to extend into the building line of an adjacent structure.

The arrangement herein shown also eliminates the use of a short section of stairs, to the end of which the ladder is usually pivoted. This stair section is provided and inclined so that the pivot of the ladder may be positioned to bring the end of the counterbalance arm within the building line of the structure to which the device is secured.

A further object of the invention is to produce a means whereby the ladder may be held in its lowered position, after the removal of the weight which caused it to assume this last named position. It is also an object to construct an arrangement whereby the ladder and the means which elevates the same, coöperate to limit the upward movement of the ladder and to permit of an adjustment whereby this upward position may be varied to suit various conditions.

It is an object to produce these and other advantages in a simple and expeditious manner without resulting in a corresponding reduction in efficiency.

The invention will be more readily understood when read in conjunction with the accompanying drawings, in which—

Figure 1 is a side elevation of the invention showing in dotted lines the parts in the alternate position.

Fig. 2 is a top plan view of Fig. 1;

Fig. 3 is a view of a modified construc-

tion of a connection which may be resorted to between the ladder and the means for raising same.

In the embodiment of the invention shown in the drawings the use of the usual ladder or stairs 10 and platform 11 is contemplated, each of these being provided with the usual railings 12 and 13. A counterbalance mechanism generally designated 14 is arranged to coöperate with the ladder 10 to cause same to be held in an elevated position, as shown in full lines in Fig. 1. This counterbalance 14 is so arranged that the ladder 10 may be held in a lowered position when desired, after it has been caused to assume this position; this feature being explained more in detail hereinafter.

By referring to the drawings it will be seen that the ladder 10 and the arm 15 which carries the counterbalance weights 16, normally assume positions in which they are substantially parallel to each other, and that they are pivoted to swing away from each other when the ladder is lowered. This is due to the fact that the arm and ladder carry the gears 17 and 18 which mesh with each other. It will be understood that both sides of the ladder may be provided with counterbalance weights and gears, and also that when occasion demands one set of these arms and gears may be eliminated without interfering with the satisfactory operation of the device. The arm 15 and ladder 10 and their coöperating parts may be attached to the platform 11 or may be directly attached to the building structure itself, as found convenient or desirable. Any suitable arrangement for securing these parts in position may be resorted to; that herein shown consisting of the plates 19 and 20, which are each bolted to the opposite sides of the platform 11. Each plate may be provided with the bearing 21 through which is passed the shaft 22 which extends beyond the opposite sides of the platform and has its opposite ends provided with the gears 18—18, to each of which is secured one side of the ladder 10. Each plate is provided with the stud shaft 23, one end of which is mounted in the plate, the opposite end thereof being mounted in the bracket 24. This stud shaft carries the gear 17 which in this instance is preferably secured thereto, and rotates therewith. This stud shaft has adjustably secured thereto one end of the counterbalance arm 15, the opposite end of which is

105
110

shown, extends in the same direction as the ladder 10 when the ladder is raised. The end of this arm nearest the stud shaft is provided with the hub 25 and the set screw 26, whereby the arm may be adjusted and secured to the shaft 23, which, as before stated, carries the gear 17. This end of the arm is further provided with the clamping bolt 27 which extends through a slot 28 provided in the gear 17. The arrangement just described permits the arm 15 to be adjusted so that the weights 16 will act upon the ladder 10 to hold it in its lowermost position when it has been once forced down by the weight of a person being applied thereto, instead of permitting the ladder to seek its raised position each time the ladder is overbalanced. As before stated, the free end of this arm is provided with the counterweights 16 which are shown as being held thereto by means of the bolts 29 which pass through the slot 30 provided in said arm. This arrangement permits the weights to be moved upon the arm to vary the leverage to overcome the weight of the ladder. It will further be noted that the end of the arm to which the weights are secured is bent laterally, so that these weights may act to again lower the arm, and raise the ladder when the portion of the arm between its pivot and the weights assumes a substantially vertical position; and the weight which caused the ladder to be lowered is removed. A means is provided whereby the movement of the arm 15 and ladder 10 toward each other is limited. This means consists of the stop 30 which is positioned in the path of the arm 15, and secured to the ladder 10. This stop may, when found desirable, be constructed to vary the inclination of the ladder from the horizontal position in which it is shown in the drawings, to one in which the ladder is normally inclined to the horizontal. This feature results in that the free end of the ladder may be normally positioned at one side of an object which may protrude from the building to which the device is attached. This means is shown as consisting of a bolt 32 which is adjustably mounted in the stop 30. While this adjustable element is shown as operating against the end of the arm 15, it is evident that same may be positioned at any place along its length.

55 By arranging the balance arm with its weight so that it projects toward the ladder, instead of in the opposite direction, a more compact arrangement results, permitting the device to be installed in instances 60 and under conditions where a device in which the arm projects in the opposite direction could not be utilized. The device is provided with means whereby an adjustment may be had which will cause the ladder

65 to be held in its lowered position when same has once reached this position. These same means also permit the ladder to be adjusted with relation to the arm 15 so that it may be positioned at various angular positions. The means whereby the above 70 results are obtainable include the bolt 27, slot 28, and set screw 26. It can readily be seen that when the bolts 26 and 27 are loosened either or both, the arm 15 and ladder 10 may be moved from the horizontal position shown to any desired inclination. When it is desirable to hold the ladder in its lowered position after it has once been brought to this position an adjustment of the bolts 26 and 27 of the arm 15 will be resorted to, 75 permitting the arm to travel from one side of the pivot of the ladder to the other, and the force exerted by the arm in the last mentioned position will tend to retain the ladder in its lowered position.

80 I have illustrated and described the connection between the ends of the arm and the ladder as a gear connection. It can readily be seen that various arrangements at this point may be resorted to, also that 85 this mechanism can be incased so as to shield the same against the weather when desired.

85 From the foregoing explanation of the arrangement and mechanism employed it can readily be seen that the ladder will normally be held in a raised position and upon the application of weight thereto the same will be lowered; causing the arm to move upwardly to the position shown in dotted lines in Fig. 1. When the counterbalance is in this position it is evident that the center of gravity of the arm is still upon the same side of the pivot as the ladder, which fact by virtue of the connection between the ends of the arm and the ladder will cause the ladder to again be raised or swung upwardly when the weight is removed therefrom, which causes the balance arm to again be lowered to the full line position shown.

100 The device shown in Fig. 3 illustrates an arrangement whereby the ladder may be operated by a means which eliminates the use of the gears 17 and 18. In this structure the ends of the ladder 10^a and the counterbalance arm 14^a are each extended beyond their pivots to produce the levers 35 and 36. These are connected together. The lever 35 is provided with the slot 37 into which the stud 38 projects and in which it 105 operates. The ladder 10^a may be provided with the stop 30^a which limits the movement of the arm 14^a.

110 While I have herein shown various mechanisms which might be resorted to, it is 115 obvious that others different from those shown might be employed without departing from the spirit of the invention.

What I claim and desire to secure by Letters Patent is:

1. In a fire escape the combination of a ladder and a supporting structure therefor, said ladder being pivotally connected at an end to the supporting structure so as to permit it to swing to a raised or lowered position and being arranged with respect to the supporting structure so as to permit of a direct passage from the supporting structure to the pivoted end of the ladder for the application of weight to cause the lowering of the ladder when the ladder is raised, and means for raising the ladder from its lowered position after the removal of the weight, said means being pivoted at the pivoted end of the ladder and including a weighted arm which extends toward the free end of the ladder and which is arranged substantially parallel to the ladder when said ladder is in raised position.
2. In a fire escape the combination of a ladder and a supporting structure therefor, said ladder being pivotally connected at an end to the supporting structure so as to permit it to swing to a raised or lowered position and being arranged with respect to the supporting structure so as to permit of a direct passage from the supporting structure to the pivoted end of the ladder for the application of a weight to cause the lowering of the ladder when the ladder is raised and means for raising the ladder from its lowered position after the removal of the weight, said means being pivoted at the pivoted end of the ladder and including a weighted arm which extends toward the free end of the ladder, and which is arranged substantially parallel to the ladder when said ladder is in raised position, said weighted arm being so positioned that upon the full descent of the ladder the arm will bear such a relation to its supporting pivot that the ladder will remain in its lowered position.
3. In a fire escape the combination of a

ladder and a supporting structure therefor, said ladder being pivotally connected at an end to the supporting structure so as to permit it to swing to a raised or lowered position and being arranged with respect to the supporting structure so as to permit of a direct passage from the supporting structure to the pivoted end of the ladder for the application of weight to cause the lowering of the ladder when the ladder is raised, and means for raising the ladder from its lowered position after the removal of the weight, said means being pivoted at the pivoted end of the ladder and including a weighted arm which extends toward the free end of the ladder and which is arranged substantially parallel to the ladder when said ladder is in raised position, and means for adjusting the relation of the weighted arm to the ladder so that upon the full descent of the ladder the arm may bear such a relation to its supporting pivot as either to tend to raise the ladder or to retain it in lowered position.

4. In a fire escape the combination of a ladder and a supporting structure therefor, said ladder being pivotally connected at an end to the supporting structure so as to permit it to swing to a raised or lowered position, and being arranged with respect to the supporting structure so as to permit of a direct passage from the supporting structure to the pivoted end of the ladder for the application of a weight to cause the lowering of the ladder when the ladder is raised, and means for raising the ladder from its lowered position after the removal of the weight, said means being pivoted at the pivoted end of the ladder and including a weighted arm the length of which terminates within the length of the ladder and extends toward the free end of the ladder.

In witness whereof, I hereunto subscribe my name this 27th day of August, A. D., 1917.

JOSEPH M. KRYL.
